UNITED STATES PATENT OFFICE.

WILLIAM A. DU BOIS, OF CHICAGO, ILLINOIS, ASSIGNOR OF ONE-HALF TO
CHARLES O. HALE, OF SAME PLACE.

BALE-TIE FASTENING.

SPECIFICATION forming part of Letters Patent No. 290,549, dated December 18, 1883.

Application filed October 29, 1883. (No model.)

To all whom it may concern:

Be it known that I, WILLIAM A. DU BOIS, a citizen of the United States, residing at the city of Chicago, in the county of Cook and State of Illinois, have invented an Improvement of Bale-Tie Fastenings, of which the following is a specification.

My invention relates to an improvement in bale-tie fastenings, and especially to that class adapted to wire ties; and it consists in the peculiar manner of twisting the wires, herein after specified, reference being had to the accompanying drawings.

In Figures 2 and 5, A represents a wire such as is used for tying hay or other material, one end of which is twisted round itself to form the elongated loop B.

Figs. 3 and 6 represent the other end of the wire which is bent in the following manner: 20 A curve or neck, C, is formed a suitable distance from the end. The end D is then bent round to form a loop to a proper distance, where a short turn is effected to form the catch E.

Fig. 6 is substantially the same as above, with a small piece of wire twisted in with the main wire at the curve or neck C, to give more strength for baling heavy material. When the wire is passed round the bale, the loop B

is passed under the loop D at the points F 30 in Figs. 1 and 4, and over the curve or neck C. The catch E is then forced into the curve or neck C, thereby securing the loop B firmly in its position and completing the fastening, as shown in Figs. 1 and 4. The loop B being 35 thus secured, it is obvious that a double bearing is obtained on the wire at the points of contact with the neck C and catch E and the loop B at the points a a.

I am fully aware that it is not new to form 40 a bale tie or fastening with the main wire which surrounds the bale, and I do not therefore claim such, broadly, as my invention; but,

Having described my invention, what I claim as new, and desire to secure by Letters 45 Patent, is—

The wire A, bent and twisted to form the loop B, and the other end of the wire bent to form the curve or neck C, with the extreme end bent to form the loop D and catch E, substantially as herein set forth, the loop B brought together in connection with the neck or curve C and secured in place by the catch E, substantially as set forth.

WM. A. DU BOIS.
